COMBINATION ASHTRAY AND EXTINGUISHER
Marguerite Nunez, 194 Waterman St., Providence 6, R.I.
Filed Apr. 10, 1963, Ser. No. 272,021
1 Claim. (Cl. 131—236)

This invention relates to home furnishings and, more particularly, to a piece of home furnishings that falls within the category of useful and eye-pleasing novelties.

It is the prime object of this invention to provide a combination ashtray having cavities in which water may be placed for extinguishing the fire in the end of a cigarette and/or cigar, thereby making it impossible for the cigarette or cigar to accidentally start a fire by falling out of the ashtray.

Another object of this invention is to provide a combination ashtray that is especially desirable for use as an ashtray in offices or hospitals where there is considerable danger from fire accidentally started by a cigarette left in a receptacle not having the water cavities found in this invention.

Still another object of this invention is to provide a combination ashtray having interlocking parts that do not require the use of any tools for its assembly or disassembly.

Other and further objects and advantages of this combination ashtray, will be hereinafter described, and the novel features thereof defined in the appended claim.

Referring to the drawing:

FIGURE 1 is a perspective view of this invention in use as an ashtray, including a cigar and cigarette shown in phantom lines.

FIGURE 2 is a fragmentary sectional view of this invention taken along line 2—2 of FIGURE 1 as viewed in the direction indicated by the arrows.

FIGURE 3 is a top view of FIGURE 2 in its entirety, which view is also fragmentary.

FIGURE 4 is a perspective view of the candelabra portion of this invention removed from the dish and ready for use as a separate article.

FIGURE 5 is a perspective view of the ashtray per se.

Similar reference characters refer to similar parts throughout the several views of the drawing.

Having reference now to the drawing in detail, there is generally indicated by the character 8 a bon bon dish that is preferably circular as viewed from the top and having an outwardly rolled and scalloped edge 9 of any desired design. The dish is reinforced by a plurality of ribs 10, which extend radially from the center of the aforesaid dish with which they are integral. The inside wall 11 of the dish is provided with a pair of diametrically spaced horizontal projections 12 having rounded edges 13. The projections protrude inwardly from the inside wall 11 of the bon bon dish. A convex bridge 14 having a plurality of equally spaced concave recesses 15 in the upper edge thereof provides vertical support for a cone-shaped cup 16 on each end thereof. The wall 17 of each cup is provided with an external concave recess 18 in the lower outer portion thereof for the reception of the transversely rounded edge 13 of the projection 12. This construction is best shown in FIGURE 2 of the appended drawing.

Three of the ways in which this invention can be used are illustrated in FIGURES 1, 4, and 5 of the appended drawing, where it can be seen from looking at FIGURE 1 that the bon bon dish 8 has the candelabra portion,

2

which is indicated in its entirety by the reference number 19 on the drawing, placed in the bon bon dish to which it is secured by having the rounded edge 13 of each projection 12 fitted into the external concave recess 18 of each one of the cone-shaped cups 16, which are now filled with water (FIGURE 2), in which the lighted end of either cigarettes or cigars are dipped before placing the cigarettes or cigars horizontally in any one of the concave recesses 15 in the convex bridge 14, which now places the cigarettes or cigars over or near the center of the dish, in which any ashes may drop with complete safety, since they have already had the flame extinguished from the same by the water. If one desires, he may leave the water out of the cone-shaped cups 16 and place the lower end of a candle 20 in each one, thereby having a combined candelabra and ashtray. If the candelabra portion 19 of this invention is removed from the bon bon dish 8, both the dish and the candelabra portion may be used separately as illustrated by the aforesaid FIGURES 4 and 5.

There is in actual practice other uses to which this novel invention may be placed.

I have now described the construction of my invention, which may, of course, be made from any desirable fire and water-proof material such as porcelain, glass, stainless steel, or aluminum. The invention may be colored to suit one's artistic taste.

What I now claim as my invention is:

A device of the type described, comprising two spaced cups having flat bottoms and upwardly diverging sides and which are circular when viewed from the top, an arched bridge connecting the sides of said cups, the bridge having a plurality of spaced, concave recesses which are adapted to receive cigars and/or cigarettes, a receptacle which is circular when viewed from the top, the sides of the receptacle upwardly diverging at the same angle as the sides of the cups, the cups and bridge extending across the receptacle with the walls of the cups engaging the wall of the receptacle, diametrically spaced horizontal ribs extending inwardly from the walls of the receptacle and the cups having concave recesses in the sides thereof to receive the ribs, whereby the cups and bridge can be placed within the receptacle and rotated to bring the ribs into the recesses to lock the receptacle, cups and bridge together.
